(57) **CLAIM**

The ornamental design for a plant grow cabinet, as shown and described.

DESCRIPTION

FIG. 1 is a front top left perspective view of a plant grow cabinet, showing our new design;
FIG. 2 is a front view thereof;
FIG. 3 is a rear view thereof;
FIG. 4 is a right side view thereof;
FIG. 5 is a left side view thereof;
FIG. 6 is a top view thereof;
FIG. 7 is a bottom view thereof;
FIG. 8 is front top right perspective view thereof;
FIG. 9 is front bottom left perspective view thereof; and
FIG. 10 is front bottom right perspective view thereof;
FIG. 11 is an enlarged view for magnification purposes of the area denoted in FIG. 1 with reference number 11;
FIG. 12 is an enlarged view for magnification purposes of the area denoted in FIG. 2 with reference number 12; and,
FIG. 13 is an enlarged view for magnification purposes of the area denoted in FIG. 9 with reference number 13.
The figures include surface shading, which represents contour and not surface ornamentation.
The broken lines in FIGS. 1, 2, 9, 11, 12, and 13 indicating portions of the figures shown enlarged form no part of the claimed design; all other broken lines depict portions of the plant grow cabinet that form no part of the claimed design.
